Primary Examiner — Cynthia Ramirez(74) *Attorney, Agent, or Firm* — Pearne & Gordon LLP(57) **CLAIM**

The ornamental design for a lifting device, as shown and described.

DESCRIPTION

FIG. 1 is a top-front-left side perspective view of a lifting device in an open configuration, showing my new design;
 FIG. 2 is a top-front-left side perspective view of the lifting device of FIG. 1 in a closed configuration;
 FIG. 3 is a front elevational view of the lifting device of FIG. 2;

FIG. 4 is a right side elevational view of the lifting device of FIG. 2;
 FIG. 5 is a back elevational view of the lifting device of FIG. 2;

FIG. 6 is a top plan view of the lifting device of FIG. 2; and,
 FIG. 7 is a bottom plan view of the lifting device of FIG. 2.
 The broken lines in the drawings represent portions of the lifting device which form no part of the claimed design.
